UNITED STATES PATENT OFFICE.

HAROLD D. GRINNELL, OF PITTSFIELD, MASSACHUSETTS, ASSIGNOR TO THE G. C. A. MANUFACTURING COMPANY, OF PITTSFIELD, MASSACHUSETTS, A CORPORATION OF MASSACHUSETTS.

LAMP-BULB INSTALLING AND REMOVING DEVICE.

Application filed May 17, 1922. Serial No. 561,717.

To all whom it may concern:

Be it known that I, HAROLD D. GRINNELL, a citizen of the United States, and a resident of Pittsfield, in the county of Berkshire and 5 State of Massachusetts, have invented an Improvement in Lamp-Bulb Installing and Removing Devices, of which the following description, in connection with the accompanying drawings, is a specification, like 10 characters on the drawings representing like parts.

This invention relates to improvements for installing and removing incandescent lamp bulbs and other objects, and aims to provide 15 novel and improved means for manually performing these operations quickly and safely, particularly in respect to lamp bulbs suspended upon a cord or other non-rigid support in elevated positions.

20 My invention will best be understood from a description of a specific useful embodiment thereof, illustrated in the accompanying drawings, wherein—

Fig. 1 is a front elevation of the device in 25 operative relation to an incandescent bulb of the usual type, the same being illustrated in connection with an ordinary form of lamp shade, the limits of outward movement of the 30 clamping arms for gripping the shade being indicated in dotted lines;

Fig. 2, a side or edge view of the same; and

Fig. 3, a longitudinal vertical section on 35 the line 3—3 of Fig. 2, presenting a front view of the device on an enlarged scale.

Referring to the accompanying drawings, it will be observed the device comprises a bulb engaging portion and a shade gripping and supporting portion. These portions are 40 mounted in cooperative relationship upon a hollow rod or pole by means of which they are supported, operated and controlled. This rod is of indefinite variable length and adapted to enable the operator to conveniently manipulate an object when placed 45 beyond his grasp. The rod may be formed in any manner suitable to the purpose, and is preferably composed of a series of sections detachably connected so that by adding or 50 removing a suitable number their aggregate length may be readily accommodated to the required reach for operation.

As herein shown, the rod comprises permanent upper and lower tubular sections 10, 11,

jointedly connected as at 12 in any suitable 55 manner, the upper end of the rod being fitted with a fixed head 13 seated within the tubing and having an exposed portion extending beyond the rod, while the opposite end of the rod carries a handle 14 having a reduced 60 stem portion 15 extending slidably into its interior a distance preferably at least equal to the limits of movement of the handle, as hereinafter described.

The head 13 is provided with a central 65 bore to receive a sliding spindle 16 extending downward through the rod sections 10, 11, and seated in the upper end of the reduced portion 15 of the handle. The spindle 16 is extended upward through and beyond the 70 head 13 and carries at its upper end a detachable socket member 17 adapted to support a removable chuck or clutch member 18 for receiving a lamp bulb 19.

The socket member 17 has a stem 20 provided with a suitable central bore to receive the upper extremity of the spindle 16, being 75 removably secured in fixed position thereon by a set-screw 21. In the upper end of this socket member is a circular well 22 having 80 inclined side walls corresponding with the formation of a stem 23 depending from the clutch 18 and adapted to seat firmly therein, said stem being preferably fitted with a metal bushing 123 having tapering side 85 walls. To prevent accidental displacement of the clutch from its setting and supplementing the frictional resistance offered by the engagement of the stem with the socket member, I provide suitable latching means 90 in the form of a spring-pressed button 223 slidably mounted in a transverse opening in the stem 23 and extending at one end through suitable registering openings in the walls of the bushing 123 and socket member 95 17.

The clutch 18 is a hollow receptacle having the formation of an inverted frustum, the large end being open to receive a lamp bulb and the lower end being closed 100 preferably by the provision of a perforate bottom 24 (see Fig. 3) depending centrally from which is the reduced portion or stem 23, said bottom and stem being preferably integral and provided centrally with a recess 105 25 adapted to receive the nipple 26 on the bulb 19, and also with one or more marginal openings 124 which serve as air vents.

The side walls of the clutch 18 are constructed of flexible material, such as paper, rubber or thin sheet-metal, adapted to bind upon the walls of the bulb and conform to any irregularities in the surface thereof. The side walls and bottom of the clutch may be made integral, but in the present embodiment of my device these parts constitute separate elements secured together by means 10 of a bailing wire 27 enclosing the side walls about the bottom 24 and adapted to force the former into an annular groove 28 provided on the periphery of the bottom.

Pivoted in any suitable manner at their 15 lower ends to the rod 10, and preferably to the exposed portion of the head 13 by means of separate screws 29 are a pair of oppositely arranged, adjustable clamping arms 30, 30, arranged to swing toward and away from each other and designed to grip a lamp shade 31. The shade herein illustrated is detachably supported in the usual manner upon a bracket 32 carried on the lamp socket 33, and forms a depending skirt freely 25 surrounding the lamp bulb.

In the present embodiment the arms 30, 30, are constructed of metal tubing formed at their lower ends with integral bifurcated portions 34, 34, arranged to straddle the head 13 and secured thereto in the manner above described. Inserted in the upper end of the clamping arms and slidably mounted therein are shown semi-circular arm extension portions 35, 35, secured at any desired 30 elevation by means of threaded studs 36, 36, seated in said extension portions and extending through suitable longitudinal slots 37, 37, provided in the side walls of the arms 30, 30, the projecting end of each of the 40 studs being fitted with a clamping nut 38.

Mounted on the upper extremities of the arm extension portions 35 are clamping or gripping members 39, 39, adapted to grip the rim of the lamp shade 31 at opposite 45 points. As herein shown, these gripping members are secured in any suitable manner in fixed position on the arm extension portions 35, being preferably constructed of stamped sheet metal of open structure having an upper cross strip 40 formed to present a concave surface for gripping the side walls of the shade, and a convex lower strip 41, forming a support or seat extending beneath the shade and engaging its lower rim, 50 the interstice or slot intervening these portions being adapted to receive a segment of the shade rim. Those parts of the gripping members such as the strips 40, 41, engaged by the lamp shade are preferably wound 55 with tape or otherwise provided with suitable protective coverings 42.

The clamping arms 30, 30, are pivotally secured to the spindle 16 by braces 43, 43, which are attached at their outer ends preferably to integral eye members 44, 44, struck

up centrally from the arms and at their inner ends to a horizontally arranged yoke 45 slidably mounted on the spindle 16 above the rod 10 and provided with apertured ends arranged in vertical planes for attachment 70 of the braces.

The arms 30, 30, are normally held in the closed position by a coil expansion spring 46 mounted on the spindle 16 above the rod 10, said spring bearing at its lower end upon the head 13 and at its upper end against the yoke 45, a sliding collar 47 (see Fig. 3) being preferably interposed between the spring and the yoke.

In operation, the clamping arms 30, 30, 80 are first spread apart the approximate distance required for adjustment to the lamp shade, this spreading operation being accomplished by the operator by grasping the rod 10 firmly in one hand and pulling down 75 upon the handle 14 with the other hand. This downward movement of the spindle 16 will not cause the arms 30, 30, to spread until the socket member 17 is brought into contact with the yoke 45 which is then 90 forced downward in opposition to the yielding resistance of the spring 46. When the arms 30, 30, spread sufficiently to receive the shade 31 the gripping members 39, 39 are applied to the rim in the manner shown in 95 Figs. 1 and 2. The downward pull on the handle is now released and the gripping members are forced into close engagement with the shade responsive to the expansive action of the spring 46. The spindle 16 is 100 now free to be raised without disturbing the position of the clamping arms, the clutch 18, being forced upward over the outer or enlarged end of the lamp bulb and at the same time sufficient downward pull is exerted by 105 the operator upon the clamping arms to hold the lamp shade in stationary position. When the bulb is well seated in the clutch the spindle 16 is then rotated to unscrew the bulb from its socket, after which the clamping arms are again spread in the manner 110 above described for disengaging the lamp shade. Similar operations, involving the reverse action of the spindle 16, may be employed to install the bulb in the lamp socket. 115

Preliminary adjustment of the arm extension portions 35, 35, by means of the nuts 38, 38, may be necessary to give the clamping arms the required reach and to permit sufficient space between the lamp socket and 120 the lower limit of movement of the clutch for play of the clutch in installing or removing the lamp bulb. As the clutch is removable in its mounting, any one of a series of clutches having well portions of different 125 capacities but like-sized stem portions may be employed.

This part of my invention is reserved as subject matter for a separate application.

It will be apparent that my invention is 130

not restricted to the particular embodiment herein shown and that obvious modifications in the structure, combination and arrangement of its parts may be made without departing from the objects of the invention.

I claim as my invention:

1. In a device of the class described, in combination with a support, separate cooperative clamping mechanisms movably mounted on the support for application to separate objects.

2. In a device of the class described, in combination, a support, mechanism mounted on the support for gripping a lamp bulb, and separate adjustable mechanism movably mounted on the support for gripping a lamp shade.

3. In a device of the class described, in combination, a support, clutch mechanism for engaging a lamp bulb, separate mechanism for gripping a lamp shade, and means whereby said shade gripping mechanism may be moved in the direction of its length independently of said support and said bulb-engaging mechanism.

4. In a device of the class described, in combination, a support, gripping mechanism carried on said support, means for imparting rotary and reciprocating movements to said mechanism, separate gripping mechanism carried on said support and having arms enclosing said first-mentioned gripping mechanism, and means for opening and closing said arms.

5. In a device of the class described, in combination with a support, separate cooperative clamping mechanisms carried by the support, one of said mechanisms being adapted to grip a lamp shade, and the other of said mechanisms being adapted to grip a lamp bulb.

6. In a device of the class described, in combination, a support, gripping means for detachably securing said support to an object, a thrust member mounted to slide in said support, and means carried by said

thrust member adapted to be moved into and out of position for gripping a separate object.

7. In a device of the class described, in combination, a rod, a spindle mounted to slide in said rod and projecting beyond one end of the rod, a clutch mounted on one end of the spindle for gripping a lamp bulb, and means carried on the rod and cooperating with the clutch for gripping a lamp shade.

8. In a device of the class described, in combination, a support, clamping arms movably secured to the support and adapted to be moved into and out of position for gripping an object, and cooperative means carried by said support and adapted to be moved independently of the clamping arms into and out of position for gripping a separate object.

9. In a device of the class described, in combination, a support, clamping mechanism including arms movably secured to the support, means for actuating the arms toward and away from the support for gripping an object, separate clamping mechanism carried by the support for cooperative relationship with said clamping arms, and means for imparting a reciprocating movement to said separate clamping mechanism.

10. In a device of the class described, in combination, a tubular support, a thrust member mounted to slide within said support and extending beyond one end of the support, clamping arms pivoted to the upper end of the support and arranged to swing toward and away from each other, a sliding member carried on said extended portion of the thrust member, braces pivotally connected to the clamping arms and to said sliding member, and spring means for actuating said sliding member outward to close the clamping arms.

In testimony whereof, I have signed my name to this specification.

HAROLD D. GRINNELL.
